UNITED STATES PATENT OFFICE.

JAMES McNAMARA, OF MONTREAL, QUEBEC, CANADA, ASSIGNOR TO MERRANTHALER LINOTYPE COMPANY, A CORPORATION OF NEW YORK.

MATRIX FOR MONOLINE-MACHINES.

No. 850,094.

Specification of Letters Patent.

Patented April 9, 1907.

Original application filed July 14, 1905, Serial No. 269,748. Divided and this application filed December 29, 1906. Serial No. 360,070.

To all whom it may concern:

Be it known that I, JAMES McNAMARA, temporarily residing in the city of Montreal, Province of Quebec, Dominion of Canada, have invented a new and useful Improvement in Matrices for Monoline-Machines, of which the following is a specification.

My invention has reference to an improved matrix, designed more particularly for use in the monoline-machine or line-casting machine represented in application for Letters Patent of the United States filed by me on the 14th day of July, 1905, Serial No. 269,748. 10 In this class of machines elongated matrices provided with suspending hooks at their upper ends are provided each in one vertical edge with a series of independently-usable characters and in the opposite edge with a 20 corresponding series of notches to coöperate with alining devices, whereby the matrices in a composed line are held temporarily in such relation as to maintain exact alinement of the selected characters therein. In the 25 action of these machines the matrices are permitted to fall one after another into an assembling-box, from which they are delivered laterally to the line, their descent being arrested at one side or another by underlying movable stop-plates in order to bring the selected character to the assembling-level. When the descending matrices strike upon the arresting or stopping devices, there is a tendency to rebound, in consequence of which they are liable to assume 35 incorrect positions, so that proper action of the machine is prevented. In the original machines this rebound was prevented by a spring-pawl or dog, which acted against the 40 matrices during their descent and engaged in their alining-notches successively. In practice it was found that the detenting dog or pawl was uncertain in action and that it caused a wear of the alining-notches sufficient to prevent the proper action of the 45 alining devices, in consequence of which the type characters on the slugs and in the resulting print were frequently out of line.

In my improved machine described in the 50 application above named I have provided a series of keepers or detents adapted to engage the lower ends of the matrices, so that

each one will be held down in place the instant it is arrested. The machine also includes distributing mechanism containing a series 55 of overlapping plates, from one end of which the matrices are suspended, the arrangement being such that the matrices suspended from one plate will be overlapped by the next plate while they are being raised to the distributing-level. In order to meet the peculiar conditions of this machine, I construct my improved matrix with a suspending-hook, with the matrix in one edge and the alining-notches in the opposite edge in substantially the same manner as heretofore; but I further provide them with a special notch near the lower end adapted to be engaged by one or another of the keepers.

In the accompanying drawings, Figure 1 70 represents a side view of a matrix constructed in accordance with my invention; Fig. 2, a front edge view of the same; Fig. 3, a rear edge view of the same. Fig. 4 is a side view illustrating the manner in which the 75 lower end coöperates with the arresting device and the keeper.

Referring to the drawings, A represents a matrix consisting of a continuous flat plate having parallel vertical edges and a suspending-hook a at the upper end. One of the vertical edges contains a series of notches each with an intaglio character or matrix proper a' therein. There are usually from ten to twelve of these characters of similar width in 85 each matrix. The opposite edge of the matrix is provided with a corresponding number of notches a^2 , designed to coöperate with the alining devices. So far as described the matrix resembles those heretofore in use. 90

In constructing my improved matrix I continue the body portion below the lowest character and form therein near the lower extremity a special notch a^3 , preferably in the edge which contains the matrices, to coöperate with the series of keepers or detents hereinafter described. The corner of the matrix below the notch a^3 is rounded or beveled, as shown, in order that it may readily pass the engaging or detaining devices. In 95 instead of forming the hook a with the rounded top surfaces, as before, I form it with a flat surface on the top, as shown at a^4 .

In Fig. 4, B B' B² B³ represent a series of

horizontally-movable stops or plates used in the machine to arrest the descending matrices at different heights, according to the character which is to be brought into use.

5 C C' C² C³ C⁴ are a series of horizontally-movable keepers or detents. The matrix descends between the stops and the keepers and after being arrested by one of the former is instantly engaged by one of the latter, the 10 stop being moved under the matrix from one side, while the keeper is moved into the notch a³ from the opposite side.

Owing to the existence of the special notch at the lower end of the matrix, I am enabled 15 to make use of the series of keepers or detents to lock the matrix down in each of the positions in which it is arrested, and this without having the detents or locking devices ride over or against the upper edges of 20 the matrix containing the characters and alining-notches. All devices heretofore provided for preventing the rebound of the matrices were compelled to ride against their edges, and the result was a mutilation of the 25 alining-notches or of the type characters.

Having described my invention, what I

claim, and desire to secure by Letters Patent, is—

1. A matrix for a monoline-machine comprising a body portion provided with a suspending-hook, with the matrix characters in one edge, with the alining-notches in the opposite edge, and also with a special detaining-notch a³ below the characters. 30

2. A monoline-matrix comprising a body portion with a suspending-hook at the top, a series of matrix characters in one edge, and a single detaining-notch in said edge below the characters. 35

3. A monoline-matrix comprising a body portion having in one edge a series of characters, in the opposite edge a like number of alining-notches, and also at the lower end a special detaining-notch a². 40

In testimony whereof I hereunto set my hand, this 26th day of December, 1906, in the presence of two attesting witnesses.

JAMES McNAMARA.
